UNITED STATES PATENT OFFICE.

FRANK H. BRISTOW, OF BROOKLYN, NEW YORK.

GAME.

SPECIFICATION forming part of Letters Patent No. 393,291, dated November 20, 1888.

Application filed February 6, 1888. Serial No. 263,100. (No model.)

To all whom it may concern:

Be it known that I, FRANK H. BRISTOW, a citizen of the United States, residing at Brooklyn, county of Kings, and State of New York, 5 have invented a Novelty in Games, of which the following is a specification.

This invention relates to a game similar to that known as "checkers" or "draughts," and like it is played between and by two persons, 10 each player having a set of twelve checkers or men termed, respectively, "Democrats" and "Republicans," and the object of the player is to move his men so that one of them (previously nominated or selected) will succeed in reaching an indicated square on the 15 opposite side of the table or board from which the opposing party's nominee starts, in which case he wins the game, and that party's nominee is said to have been elected. The men 20 are moved and jump or take opposing men when the opportunity offers the same as in checkers. Two additional men are also used, representing "Labor" and "Prohibition" parties, their object being to impede and destroy as 25 many men as possible by jumping or taking, and as they can only move by jumping they are stationary until men of either party happen to be placed next to them, which they must jump. The man jumped or taken is 30 moved from the board, with the exception of the two nominees. These must be returned to their starting-point.

In the accompanying drawing, which forms a part of this specification, the arrangement 35 of the men upon the board is plainly shown. The board or table A is divided into sixty-four squares, thirty-two of which (shown shaded at B to represent color) are used, the remaining thirty-two being blank, as shown at C. The alternate arrangement of squares B and C is well 40 known as the ordinary "checker-board." The checkers or men D, or Democrats, are arranged

in order on the squares on one side shown shaded, and the men R, or Republicans, are similarly arranged on the other side, the squares B', 45 indicated by the star shown, being covered by the nominees of their respective parties. The men P and L, representing the Labor and Prohibition parties, are placed, as shown, between the two contending parties, and are permitted 50 movement by jumping (in any direction on the squares B) any man that comes near them, except each other, while they themselves cannot be jumped. The men D and R, however, may only move in the direction of the 55 opposite party, with the object, as before stated, of placing their nominee on the star square of the rear line on the opposite side.

The men may be represented, as in checkers, by pieces of wood or other material suitably 60 shaped, having upon them the names or photographs of prominent politicians, and their parties designated by different colors, such as white for Democrats, black for Republicans, 65 blue for Prohibitionists, and red for Labor. Any two men of the two large parties on being nominated are placed on the star-square, and the game, which I term "Political checkers," proceeds as already described.

Having thus described my invention, the 70 following is what I claim as new therein and desire to secure by Letters Patent:

A game apparatus similar to checkers or draughts, consisting of a checkered or equivalent field, two sets of pieces (men) of different 75 color, each set having pictures, names, or other designations upon them, and two additional pieces, (men,) also of different color, with other pictures, names, or designations upon them, as and for the purpose explained.

FRANK H. BRISTOW.
